CLAIM

The ornamental design for a storage box as shown and described.

DESCRIPTION

FIG. 1 is a front, right, and top perspective view of a storage box showing the claimed design;

FIG. 2 is a rear, left, and top perspective view thereof;

FIG. 3 is a front elevational view thereof;

FIG. 4 is a rear elevation view thereof;

FIG. 5 is a left side elevational view thereof, wherein the right side elevational view is omitted because it is a mirror image of the left side elevational view;

FIG. 6 is a top plan view thereof;

FIG. 7 is a bottom plan view thereof; and,

FIG. 8 is an enlarged view of portion 8 shown in FIG. 1. The even-dashed broken lines in the drawings depict portions of the storage box that form no part of the claimed design.

The dot-dash broken lines in the drawings represent boundaries of the enlarged portions and form no part of the claimed design.
